Primary Examiner — Joseph Kukella*Assistant Examiner* — Arva P Adams(74) *Attorney, Agent, or Firm* — Weintraub Tobin; Eric Caligiuri(57) **CLAIM**

The ornamental design for a large liquid tumbler, as shown and described.

DESCRIPTION

FIG. 1 is a top and side perspective view of a large liquid tumbler according to the present invention;

FIG. 2 is a first side view of the large liquid tumbler of FIG. 1;

FIG. 3 is a second side view of the large liquid tumbler of FIG. 1;

FIG. 4 is a third side view of the large liquid tumbler of FIG. 1;

FIG. 5 is a top view of the large liquid tumbler of FIG. 1; and,

FIG. 6 is a bottom view of the large liquid tumbler of FIG. 1.

The broken lines shown in the drawing are for illustrative purposes only and form no part of the claimed design.
